UNITED STATES PATENT OFFICE.

THOMAS E. O'CONNOR, OF MINNEAPOLIS, MINNESOTA.

BURGLAR ALARM.

Application filed November 28, 1924. Serial No. 752,601.

My invention has for its object to provide an extremely simple and highly efficient burglar alarm intended for general use but especially adapted to be installed in buildings of

5 various different types and designed to be actuated by the movement of a door, window, loose step or the like.

To the above end, generally stated, the invention consists of the novel devices and 10 combinations of devices hereinafter described and defined in the claim.

In the accompanying drawings, which illustrate the invention, like characters indicate like parts throughout the several views.

15 Referring to the drawings:

Fig. 1 is a fragmentary view showing the inside of a room having an inwardly swinging entrance door and a window comprising upper and lower sliding sash;

20 Fig. 2 is a fragmentary view of the trip mechanism as applied to the door and its frame casing, on an enlarged scale;

Fig. 3 is a detail view with some parts sectioned on the line 3—3 of Fig. 2;

25 Fig. 4 is a detail view with some parts sectioned on the line 4—4 of Fig. 2, on an enlarged scale;

30 Fig. 5 is a detail view with some parts sectioned on the line 5—5 of Fig. 1, on an enlarged scale;

Fig. 6 is a detail view with some parts sectioned on the line 6—6 of Fig. 5; and

35 Fig. 7 is a wiring diagram and the trip mechanism for the door and its frame casing.

40 For the purpose of showing the invention applied in working order, there is illustrated in the drawings a room 8 having an entrance door 9 hinged for horizontal inward swinging movement in a door frame having a casing 10. The room is also provided with a window comprising upper and lower sashes 11 and 12, respectively, slidably mounted in a frame having a casing 13.

45 Referring now in detail to the invention, the numeral 14 includes a transformer the primary coil of which is in a primary circuit 15, and the secondary coil of which is in a secondary circuit 16. Both of these circuits 15 and 16 are normally open and have 50 interposed therein a double knife switch 17 for simultaneously opening and closing said circuits. Interposed in the primary circuit 15 is a socket 18 in which is secured a plug 19 connected by a lamp or duplex cord 20 to a plug 21 secured in a socket 22 in a supply or lamp circuit 23 leading from any suit-

able source. The invention also includes a light bulb 24 in the primary circuit 15, and two bells 25 and 26 in the secondary circuit 16.

55 The transformer 14, switch 17, socket 18, light bulb 24 and bell 25 are all mounted in a casing 27 which, as shown, is secured to the top member of the casing 10 directly over the door 9. The light bulb 25 is mounted directly back of a lens or light opening 28 in the front of the casing 27 so that the light from said bulb will shine therethrough. The bell 26 may be located at any distant point somewhere outside of the room 8. The 60 socket 22, as shown, is secured to the ceiling of the room 8 and the socket 18 is mounted on the left hand end of the casing 27. The switch 17, as previously stated, is open and may be closed by trip mechanisms, one of 65 which is arranged to operate by the opening movement of the door 9 and the other of which is arranged to operate by the raising movement of the lower window sash 12.

70 The trip mechanism actuated by the door 80 includes a pivoted flat horizontal finger 28, a depending pivoted latch 29 which supports the free end of said finger, a weight 30 supported on the finger 28, and a sliding bolt 31 arranged to be projected back of the latch 75 29. Said finger 28 is pivoted to a back plate 32 for downward swinging movement and the latch 29 is pivoted to said plate for swinging movement in the direction of the opening movement of the door 9. The back 80 plate 32 is secured to the casing 10 and the sliding bolt 31 is secured to the door 9. The latch 29 is provided with an inturned lug 85 33 at its free end on which rests the free end of the finger 28. The weight 30 is held 90 in an open ended guide 34 on the back plate 32 and is connected by a cable 35 to the knife switch 17 and runs over a guide sheave 36.

95 In case the door 9 is opened when the sliding bolt 31 projects back of the latch 29, said latch will be swung by said bolt in the same direction as the opening movement of the door and thereby carry its supporting lug 33 from under the finger 28 and allow the same to drop under the action of the weight 100 30 and release said weight. As the weight 30 drops, it draws on the cable 35 and closes the switch 17, and hence the circuits 15 and 16 thereby lighting the lamp 24, as a visual alarm, and ringing the bells 25 and 26, as 105 audible alarms.

110 The mechanism for actuating the alarm

in case the lower sash 12 of the window is raised, is substantially the same as that just described and includes a pivoted flat horizontal finger 37, a depending pivoted latch 38 which supports the free end of said finger, a weight 39 supported on the finger 37 and a sliding bolt 40 having a laterally bent end 41 arranged to engage a lug 42 on the latch 38 in case the lower sash 12 is raised. Said finger 37 and latch 38 are pivoted to a back plate 43 secured to the casing 13, and the sliding bolt 40 is secured to the top rail of the lower window sash 12. The weight 39 is mounted within an open ended guide 44 secured to the back plate 43. The latch 38 is provided with an inturned lug 45 on which the free end of the finger 37 rests. The weight 39 is secured to the cable 35 by a cable 46 which runs over a guide sheave 47 on the casing 13.

Obviously, if the lower sash 12 was raised only a very little, the laterally bent end 41 of the bolt 40 will engage the lug 42 and cam the latch 38 outward sufficiently to carry its lug 45 from under the finger 37 and allow the same to drop under the action of the weight 39. As the weight 39 drops, it draws on the cords 46 and 35 and closes the switch 17, and hence the circuits 15 and 16, thereby lighting the lamp 24, as a visual alarm, and ringing the bells 25 and 26, as audible alarms. By retracting the sliding bolt 40, the lower sash 12 may be raised or lowered without actuating the alarm.

To permit the occupant of the room 8 to open the door 9 from the outside without actuating the alarm, or leave the room and thereafter set the mechanism to be actuated by the door in case it is opened, there is extended through said door 9 a short shaft 48 having on its inner end a radially extended finger 49 for sliding the bolt 31. This finger 49 projects through an aperture in the bolt

31 with freedom for angular movement in respect thereto. On the outer end of the shaft 48, is a knob 50 by which said shaft may be turned to operate the sliding bolt 31. To prevent the knob 50 from being actuated by an unauthorized person the same is mounted in a cover-equipped box 51 set into the outer face of the door 9 and has a bearing sleeve 52 in which the shaft 48 is turnably mounted. The cover of the box 51 is secured in position by a lug 53 arranged to interlock with said box and a key-actuated lock 54. A finger piece 55 on the sliding bolt 40 will prevent the same from turning at the time its laterally bent end 41 engages the lug 42. To permit the switch 17 to be opened when resetting the trip mechanism, the casing 27 is provided at its top with a lock-equipped cover 56 located directly over said switch, see Fig. 5.

It is, of course, understood that any desired number of doors or windows may be equipped with mechanism for actuating the alarm. If desired the alarm may be actuated by a mechanism operated by the depression of a loose step.

What I claim is:

The combination with an element to be tripped and a tripping member applicable to a door or window of tripping mechanism for the element including a support hinged for swinging movement in a vertical plane, a latch releasably holding the support in a horizontal position and extending in the path of movement of the tripping member, a weight loosely resting on the support, and a connection from the weight to the element to trip said element when said latch is operated by the tripping element to release said support and drop the weight therefrom.

In testimony whereof I affix my signature.

THOMAS E. O'CONNOR.
